Thermador's Glowing Blue LED Light Dishwasher, available in <http://blog.lightopiaonline.comm>, announced Nov. 17, 2013 [online], [site visited Apr. 6, 2022], Internet URL: <http://blog.lightopiaonline.com/lighting-videos/thermadors-glowing-blue-led-light-dishwasher/> (Year: 2013).*

Primary Examiner — Amy C Wierenga*Assistant Examiner* — Jenny lou M Binas(74) *Attorney, Agent, or Firm* — McGarry Bair PC**CLAIM**

The ornamental design for a light for dishwasher, as shown and described.

DESCRIPTION

FIG. 1 is a perspective view of a light for dishwasher showing our new design, which is illustrated in its environment, on a spray manifold in a dishwasher;

FIG. 2 is a perspective view the light for dishwasher from FIG. 1;

FIG. 3 is a front view thereof;

FIG. 4 is a right side view thereof, the left side view being a mirror image thereof; and,

FIG. 5 is a top view thereof.

The broken line showing of the dishwasher in FIG. 1 is for the purpose of illustrating environmental structure and forms no part of the claimed design. All other broken lines shown in the figures depict portions of the light for dishwasher that form no part of the claimed design.
